CLAIM

The ornamental design for a dispensing container, as shown and described.

DESCRIPTION

FIG. 1 is a front elevational view of a dispensing container showing our new design, the rear elevational view, the right side elevational view and the left side elevational view being identical;

FIG. 2 is a top plan view thereof; and,

FIG. 3 is a bottom plan view thereof.

The broken line showing of a dispensing nozzle is for illustrative purposes only and does not form part of the claimed design.

FIG. 1

FIG. 2

FIG. 3
